UNITED STATES PATENT OFFICE.

HORACE F. GRUMAN, OF JACKSON, MICHIGAN, ASSIGNOR OF ONE-THIRD TO D. R. COHEN
AND ONE-THIRD TO S. R. COHEN, BOTH OF DETROIT, MICHIGAN.

TENSION DEVICE FOR YARN.

1,243,162.

Specification of Letters Patent. Patented Oct. 16, 1917.

Application filed May 12, 1917. Serial No. 169,272.

To all whom it may concern:

Be it known that I, HORACE F. GRUMAN, a citizen of the United States, residing at Jackson, in the county of Jackson and State of Michigan, have invented certain new and useful Improvements in Tension Devices for Yarn, of which the following is a specification.

My invention consists of an improved tension device for yarn. One object of my invention is to provide a tension device of the above mentioned type that can be worn upon the finger, and which will be particularly adapted for use by ladies while tatting, 15 knitting, or crocheting.

Another object is to so construct my invention that it can be easily held upon the finger and will keep the yarn under an even tension.

20 A further object is to so construct my invention that the yarn can be easily placed therein and will not accidentally pull out after once inserted.

A still further object is to so construct my 25 improved device that the degree of tension on the yarn can be easily varied and so that yarns of various thicknesses can be used in connection therewith.

Another object is to so make my invention that it will be durable, neat, light in weight, and of simple construction.

These objects, and other advantageous ends which will be described hereinafter, I attain in the following manner, reference 35 being had to the accompanying drawings in which—

Figure 1 is a perspective view of my invention.

Fig. 2 is a top plan view drawn on an 40 enlarged scale.

Fig. 3 is a section on the line 3—3 of Fig. 2.

Fig. 4 is a section on the line 4—4 of Fig. 2.

45 Referring to the drawings, 1 is a ring preferably made of metal, split at 2 permitting expansion to fit fingers of various sizes. An extension 3 projects beyond the ring 1 in the direction of its width, and a portion 4 which is preferably made integral with the extension 3, is spaced above the extension 3 and top of the ring 1.

The portion 4 has a turned edge 5, and registering threaded holes 6 and 7 are respectively formed in the turned edge 5 and

portion 4 to receive an adjusting screw 8. A spring 9, preferably made of sheet metal, has an edge soldered or otherwise suitably secured adjacent the intersection of the extension 3 and the portion 4 (see Fig. 3). 60

The spring 9 has a portion 10 which is normally raised free of the upper surface of the extension 3 and upper surface 12 of the ring 1. Furthermore, the spring 9 is positioned directly below the lower end of 65 the adjusting screw 8, so that an inward movement of the screw 8 will force the spring 9 toward the extension 3 and surface 12 of the ring 1.

The spring 9 has a wide end 13 directly 70 above the surface 12 of the ring 1 and this end 13 has elongated notches 14 and 15. These notches extend inwardly at angles to the edge 16 and the inner ends of the notches 14 and 15 have curved recesses 17 and 18 75 respectively into and out of which the yarn 19 passes (see Figs. 1, 2, and 4).

It will be noted that by the angular disposition of the elongated notches 14 and 15 as shown in Fig. 2, vertical planes passing 80 through each of said notches will intersect the axis of the ring 1 at an angle other than ninety degrees (90°), thus any movement of the device upon the finger during the operation of the yarn will not cause the 85 yarn to slip out of the recessed portion of the notches, since a movement of the device is naturally in the direction of the axis of the ring or substantially so. In any event, however, the fact that the yarn passing between the recessed portions 17 and 18 extends at an angle other than ninety degrees 90 (90°) to the notches, will prevent the yarn from accidentally working out of the notches. 95

The yarn as above noted passes in and out of the recesses 17 and 18 and also between the lower face of the spring 9 and the surface 12 so that by longitudinal adjustment of the screw 8, various degrees of 100 pressure may be applied to the yarn between the spring 9 and the said surface 12 of the ring 1.

By forming the portion 5 as above noted, a slight resilient action is attained between the turned edge 5 and the portion 4, and since each of the holes 6 and 7 is screw-threaded and the turned edge 5 naturally tends to move slightly away from the portion 4, the screw 8 will be locked against 110

accidental rotation, thus preventing the loosening of the tension. Furthermore, I preferably make the surface 12 slightly flat so as to provide a relatively large area for the engagement of the yarn 19.

A device made in accordance with the above description will be extremely practical in use, since it can be readily held upon the finger, and the yarn as it is drawn thereby through by the take-up in the fabric being produced, will be under even tension, thus securing a greater perfection in the work.

While I have described my invention as taking a particular form, it will be understood that the various parts of my invention may be changed without departing from the spirit thereof, and hence I do not limit myself to the precise construction set forth, but consider that I am at liberty to make such changes and alterations as fairly come within the scope of the appended claims.

Having thus described my invention, what I claim as new and desire to secure by Letters Patent is:

1. A tension device including a ring, a part fixed thereto and having a portion spaced from the outer surface of the ring, a spring interposed between said portion and the ring, said portion having a threaded hole therein and a turned edge, said turned edge having a threaded hole, and a screw fitting said holes and designed to engage said spring, substantially as described.

2. A tension device including a ring, a part fixed thereto and having a portion spaced from the outer surface of the ring, a spring interposed between said portion and the ring, an adjusting screw mounted in said portion and having an end adapted for engagement with the spring to push the spring toward the ring, said spring having an end portion provided with notches, said notches

being included in planes extending at an angle to the axis of the ring, substantially as described.

45

3. A tension device including a ring, a part fixed thereto and having a portion spaced from the outer surface of the ring, a spring interposed between said portion and the ring, an adjusting screw supported in said portion for engagement with the spring to push the spring toward the ring, said spring having an end portion provided with notches, said notches being included in planes extending at an angle to the axis of the ring, 50 each of said notches having an enlarged recess at its inner end, substantially as described.

55

4. A tension device including a ring having a part extending therefrom, said part having a portion spaced therefrom and above the ring, a spring secured between said extending part and said spaced portion, an adjusting screw supported by said portion and designed to move the spring toward the 60 outer surface of the ring, substantially as described.

60

5. A tension device including a ring, a part fixed thereto and having a portion spaced from the outer surface of the ring, a spring 70 interposed between said portion and the ring, and an adjusting screw mounted in said portion and having an end adapted to engage with the spring to push the spring toward the ring, said spring having an end 75 portion provided with notches, substantially as described.

In testimony whereof I have signed my name to this specification in the presence of two subscribing witnesses.

HORACE F. GRUMAN.
